[57] CLAIM

The ornamental design for a shaker cap for container, as shown and described.

DESCRIPTION

FIG. 1 is a top perspective view of a shaker cap for container showing my new design;

FIG. 2 is a right side view of FIG. 1;

FIG. 3 is a left side view of FIG. 1;

FIG. 4 is a front view thereof;

FIG. 5 is a rear view thereof;

FIG. 6 is a top plan view thereof;

FIG. 7 is a bottom plan view thereof;

FIG. 8 is a top perspective view thereof with the lid fully open;

FIG. 9 is a top perspective view thereof with the lid fully closed;

FIG. 10 is a cross-section thereof on line 10—10 in FIG. 6; and,

FIG. 11 is a cross-section thereon on line 11—11 in FIG. 6.

FIG. 1

FIG. 3

FIG. 4

FIG. 5

FIG. 8

FIG. 9

FIG. 10

FIG. 11
